Primary Examiner — Amanda Christensen(74) *Attorney, Agent, or Firm* — Plumsea Law Group, LLC(57) **CLAIM**

The ornamental design for an electronics charger as shown and described.

DESCRIPTION

FIG. 1 is a perspective view of an electronics charger showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The evenly-spaced broken lines illustrate portions of the electronics charger that form no part of the claimed design. The dash-dot broken lines represent boundaries of the claimed design and form no part of the claimed design.

1 Claim, 7 Drawing Sheets(56)
